AUTOMATIC STARTER CONTROL

Paul H. Maurer, Elmira, N. Y., assignor to Eclipse
Machine Company, Elmira Heights, N. Y., a
corporation of New York

Application October 27, 1933, Serial No. 695,422

3 Claims. (Cl. 290—38)

This invention relates to an automatic starter control and more particularly to a device for automatically actuating a starting mechanism under the control of the operator, for deenergizing the starting mechanism when the engine starts, and for cranking the engine in case of engine stall.

It is an object of the present invention to provide a novel starter control which is reliable and efficient, positive in action and simple in construction.

Another object is to provide such a device which is effective to prevent operation of the starting mechanism in case of an engine backfire.

Another object is to provide such a device which is substantially independent of temperature variations or other operating conditions of the engine.

A further object is to provide such a device which is adapted for use in conjunction with engines having positive pressure fuel supply systems, and which utilizes such positive pressure in the controlling operation.

Another object is to provide such a device which includes means for controlling the dissipation of the fuel pressure after the engine stops, to thereby control the time of restarting in case of engine stall.

Further objects and advantages will be apparent to those skilled in this art from the following description taken in connection with the accompanying drawings in which:

Fig. 1 is a partly diagrammatic illustration of an internal combustion engine with a preferred embodiment of the invention combined therewith, part of the controlling means shown on an enlarged scale;

Fig. 2 is a vertical substantially midsectional view of the novel starter control device shown in Fig. 1, on an enlarged scale;

Fig. 3 is a section taken substantially on the line 3—3 of Fig. 2, on a further enlarged scale;

Fig. 4 is a semi-diagrammatic view of a second embodiment of the invention; and

Fig. 5 is a similar view of a third embodiment of the invention.

Referring first to Fig. 1 of the drawings, there is illustrated an internal combustion engine indicated generally by the numeral 1 having a fuel system including a fuel supply tank 2, a conduit 3 leading therefrom to an engine-driven fuel pump 4 by which the fuel is pumped through a conduit 5 to a carburetor 6 mounted on the fuel intake 7.

It will be understood that these elements are all of the usual or any preferred type, the fuel pump, as illustrated in Fig. 2, being of the usual engine-driven type by which a constant fuel pressure is maintained as long as the engine is in operation.

As here illustrated, the pump 4 comprises a body or shell 8 mounted on the side of the engine casing 9 and having a lever 11 pivoted on a suitable bearing 12. The upper end 13 of lever 11 is arranged to bear on an actuating element in the form of a slidably ram 14 which is preferably actuated from the cam shaft of the engine in any suitable manner, so that rotation of the cam shaft causes oscillation of the lever 11 against the pressure of a spring 15. A second lever 16 is also pivoted on the bearing 12 and arranged to actuate a plunger 17, the upper end of which is centrally attached to a flexible diaphragm 18. The diaphragm 18 and plunger 17 are biased toward their upper positions, as illustrated, by a spring 19, and an abutment 21 is provided on the lever 16 in position to engage the lever 11, whereby motion of the lever 11 in a clock-wise direction is transmitted to the lever 16 to thereby retract the plunger 17 and flex downwardly the diaphragm 18.

The diaphragm 18 acts as a closure for a chamber formed by a casing element 22 having an inlet connection 23 through a check valve 24. Said casing element is also provided with an outlet check valve 25 communicating with an outlet connection 26 to which the conduit 5 leading to the carburetor is attached. Operation of the pump 4 thus develops fuel pressure in the outlet 26, and since the diaphragm is moved through its compression stroke by the spring 19, the fuel pressure corresponds to the expansive force of the spring 19.

Referring again to Fig. 1 of the drawings, an electrical starting system for the engine is provided comprising a battery 27 grounded at 28 and connected by a lead 29 to an automatic starter control element indicated by numeral 31. This device comprises a magnetic starting switch 32, closure of which completes a starting circuit through lead 33 to the starting motor SM which is grounded as indicated at 34.

A control circuit for the magnetic starting switch is provided comprising battery lead 29, a manual switch 35 which is preferably the ignition switch of the engine, lead 36, lead 37, solenoid 38 of the magnetic starting switch, lead 39, a fixed contact 41 and a contact 42 mounted on a spring strip 43 which is grounded as indicated at 44 to 55

complete the control circuit. The spring strip 43 is arranged to be bent backward to open contacts 41, 42 by means of a lever 45 pivoted at 46, the free end of which is provided with a roller 47 arranged to engage a weight member 48 on the free end of the spring strip 43. Lever 45 is provided with a pin 49 extending laterally between a pair of flanges 51 and 52 fixed to a magnetic plunger 53 which is normally retained in its upper position by a spring 54 but is arranged to be moved downward to actuate the lever by means of a coil 55 energized from the cranking circuit through a lead 56 and grounded as indicated at 57. A generator coil 58 also grounded at 57 and connected by a lead 59 to an engine-driven generator G, is provided for retaining the plunger 53 in its lower position and thereby holding contacts 41, 42 open as long as the engine is self-operative. A single turn coil 61 is provided in the cranking circuit for opposing the coil 55 and preventing the retraction of the plunger 53 during the cranking operation until the coil 61 has been weakened by the release of the load on the starting motor when the engine starts.

It will be understood that the fuel pump 4 as so far described is of conventional construction, and the starter control unit 31 above described is in general similar to that described and claimed in the patent to Loehr and Burdick 1,912,904, and no claim is here made of novelty with respect to these elements.

According to the present invention, a control element indicated generally by numeral 65 is provided in the control circuit between leads 36 and 37 thereof for the purpose of opening the control circuit in response to fuel pressure built up by the fuel pump 4. Referring to Figs. 2 and 3 of the drawings, it will be seen that this device comprises a body member 66 providing a chamber 67 and formed with an inlet element 68 adapted for threaded engagement in the casing element 22 and with an intake check valve 69. A bleeder connection 71 is provided for gradually dissipating the pressure in the chamber 67 after the pump has ceased to operate, the rate of flow through this connection being regulated by suitable means such as a disc 72 having a suitable small opening therein. The fuel escaping through this connection is returned to the feed line 3 through a suitable conduit 73.

The chamber 67 is closed by a flexible diaphragm 74 carrying centrally thereof a plunger 75. A cap 76 is formed to cover the diaphragm 74 and is suitably fixed to the body 66 as indicated at 77. This cap carries two insulated binding posts 78 and 79. A resistor 81 is arranged to connect the binding posts 78 and 79 and is designed with such a value as to limit the current passing therethrough to a mere holding value for the magnetic starting switch 32. This resistor is normally bridged by a pair of contacts 82 and 83 connected respectively to the binding posts 78 and 79. In order to open these contacts in response to fuel pressure in the chamber 67, contact 82 is mounted on a spring strip 84 having an aperture 85 (Fig. 3) arranged to receive the upper end of the plunger 75, and said plunger is provided with a shoulder 86 arranged to engage the strip 84 and open the contacts upon upward deflection of the diaphragm 74.

In the operation of this embodiment of the invention, starting with the parts in the positions illustrated, closure of the ignition switch 35 completes the control circuit through contacts 82, 83,

solenoid 38 and contacts 41, 42 to the ground at 44 whereby the starting switch 32 is closed and cranking thereby initiated. As soon as the engine starts to turn over, the pump 4 builds up pressure in the output connection 26 in the usual manner, which pressure is communicated through check valve 69 to the chamber 67, causing contacts 82, 83 to be opened by the flexure of diaphragm 74. The opening of these contacts causes the resistor 81 to be placed in the control circuit, but this does not interrupt the cranking operation.

When the engine starts, the contacts 41, 42 are opened by the operation of the lever 45 whereby the control circuit is opened and the starting switch 32 allowed to open.

This embodiment of the present invention provides means more particularly for preventing the undesired operation of the starting mechanism in case the generator G becomes inoperative for any reason such as by failure of the driving connection between the engine and generator, or in case of backward rotation of the engine such as might be caused by backfire or by a drifting backward of the motor vehicle when in gear. It will be readily appreciated that even a small rotation of the engine in either direction causes positive pressure to be rapidly built up in the chamber 67 whereby contacts 82, 83 are opened, thus preventing undesired actuation of the starting mechanism. As soon as rotation of the engine ceases, however, the pressure in the chamber 67 is gradually released through the bleeder connection 71, whereby the contacts 82, 83 are permitted to close after a predetermined time depending upon the size of the orifice in the disc 72. If the ignition switch 35 is still closed, restarting thereupon takes place in the usual manner. Inasmuch as the viscosity of the fuel remains substantially constant at all working temperatures, it will be appreciated that the time delay so secured will be dependable and satisfactorily uniform.

Attention is called to the fact that the chamber 67 forms an air dome which tends to smooth out fluctuations in pressure caused by the actuation of the fuel pump. Some commercial forms of pumps are provided with such air domes which are removable, and in such cases applicant's control device may readily be substituted bodily for such air dome without otherwise disturbing the pump further than to connect the bleeder line 73 to the feed line 3 of the pump.

The embodiment of the invention illustrated in Fig. 4 comprises a starting circuit having a battery 87 grounded at 88 and connected by a lead 89 to a magnetic starting switch 91 which in turn is connected by a lead 92 to a starting motor SM which is grounded to complete the starting circuit.

A control circuit for the magnetic starting switch 91 is provided comprising a manual switch 93 which is preferably the ignition switch of the engine and is connected by a lead 94 to the battery lead 89 and by a lead 95 to the solenoid 96 of the magnetic starting switch. According to the present invention, the control circuit includes two parallel ground connections, one normally closed and arranged to be opened upon initiation of engine rotation, and the other normally open and arranged to be closed upon initiation of the cranking operation and to be reopened when the engine becomes self-operative.

The normally closed ground connection comprises a lead 97 and a circuit controlling device 98.

- for normally closed contacts 99 and 101. Contact 99 is mounted on a spring strip 102 connected to a binding post 103 to which lead 97 is connected, and contact 101 is grounded as shown at 104.
5. Means for opening contacts 99, 101 responsive to rotation of the engine in either direction is provided in the form of a post 105 centrally mounted on a flexible diaphragm 106 and provided with a shoulder 107 arranged to engage the flexible strip 102 and open the contacts upon upward movement of the diaphragm 106. The diaphragm 106 is subjected to pressure of an engine-driven fuel pump 108 by means of a conduit 109 which connects through a suitable fitting 111 with a chamber 112 which is closed by said diaphragm. The pressure is retained in said chamber by suitable means such as a check valve 113 and is dissipated a predetermined time after the engine stops by means of a bleeder connection 114, the flow 20 through which is regulated by suitable means such as a metering screw 115.

As here illustrated, the parallel ground connection comprises a fixed contact 116 and a contact 117 mounted on an armature 118 normally held in retracted position by suitable means such as a spring 119. Means for closing said contacts upon initiation of the cranking operation are provided in the form of a current relay which as here shown comprises a three-quarter turn coil formed by the elements of the switch 91 when closed, and a magnetic element 121 energized by the current passing through said switch during the cranking operation to attract the armature 118 and thus close contacts 116, 117.

35. In the operation of this embodiment of the invention starting with the parts in the positions illustrated, closure of the ignition switch 93 completes the control circuit through the contacts 99, 101, thus energizing solenoid 96 to close the starting switch 91 and initiate the cranking operation. As soon as the cranking starts, the heavy cranking current energizes the magnet 121 sufficiently to close contacts 116, 117. When the engine begins to rotate, the pressure built up by the 40 fuel pump 108 causes diaphragm 106 to open contacts 99, 101. The starting switch 91 is maintained closed, however, by reason of the closure of contacts 116, 117.

When the engine starts, the reduction in the 50 current traversing the starting circuit caused by the release of the cranking load weakens the magnet 121 sufficiently to allow the spring 119 to open contacts 116, 117, and since contacts 99, 101 have already been opened by the fuel pressure, this 55 causes deenergization of the solenoid 96 and consequent opening of the starting switch 91. Restarting is thereafter prevented by the fuel pressure as long as the engine is rotated and for a predetermined time interval after the engine 60 stops, as measured by the dissipation of the fuel pressure from chamber 112 past the metering screw 115. It will be understood that since the fuel pump 108 operates the same for either direction of rotation of the engine, undesired actuation of the starting mechanism will be prevented in case of backward rotation of the engine as well as forward rotation thereof as previously pointed out in connection with the embodiment of the invention first described.

70. In the embodiment of the invention illustrated in Fig. 5, the starting circuit, the magnetic switch and its leads are the same as in the embodiment illustrated in Fig. 4 and the parts are similarly numbered. In this embodiment of the invention, however, the lead 97 of the control circuit is con-

nected through a resistor 122, having such a value as to limit the current to a holding value for the solenoid 96, to a lead 123 which is grounded through normally closed contacts 124, 125. Resistor 122 is normally shunted by a pair of contacts 126, 127 which are yieldably held in engagement by a spring 128.

5. Means for breaking this shunt connection responsive to engine rotation are provided comprising a plunger 129 arranged to engage the end 10 of a lever 131 carrying the contact 127. Plunger 129 is arranged to be actuated by a flexible diaphragm 132 which forms a closure for a chamber 133. Chamber 133 is connected by a conduit 134 to the engine-driven fuel pump 108, whereby 15 pressure developed by said pump causes flexure of the diaphragm to open contacts 126, 127.

Means are provided for opening contacts 124, 125 responsive to relatively high values of vacuum in the intake system of the engine which occur 20 when the engine becomes self-operative. As here shown, this is accomplished by mounting contact 125 on a pivoted lever 135, the opposite end of which is connected to be actuated by a plunger 136 which is centrally mounted on a flexible diaphragm 137. Diaphragm 137 forms a closure for a chamber 138 which is connected by a conduit 139 to the intake manifold of the engine such as illustrated at 7 in Fig. 1.

30. In this embodiment of the invention, means 30 are provided for retaining the fuel pressure in chamber 133 during the operation of the engine but permitting said pressure to be relieved when the engine stops. As here shown, this is accomplished by a by-pass valve 141 in a bleeder conduit 142, which valve is controlled by the plunger 136 in such manner that when there is no vacuum in the chamber 138 the valve 141 is opened, allowing the pressure to be dissipated through the conduit 142 and an adjustable bleeder valve 143. 40 When the plunger 136 is retracted by a vacuum in the chamber 138 the valve 141 is closed, thereby preventing the escape of fuel through the bleeder conduit 142.

45. In the operation of this embodiment of the invention, closure of the ignition switch 93 causes full energization of the solenoid 96 since the control circuit is closed through contacts 126, 127 and contacts 124, 125 to the ground. The starting switch 91 is thereupon closed, causing initiation of the cranking operation. As soon as the engine begins to rotate, the fuel pump 108 builds up pressure in the chamber 133, thus opening contacts 126, 127. Cranking is not interrupted, however, by reason of the holding current traversing the resistance 122. When the engine becomes self-operative, the resultant increase in intake vacuum operates the diaphragm 137 to open contacts 124, 125, thus opening the control circuit and thereby allowing starting switch 91 to open. 60 Subsequent reclosure of the contacts 124, 125 by reason of loss of vacuum in the intake, will not cause the starting switch 91 to close, however, since contacts 126, 127 are held open by the fuel pressure.

65. During self-operation of the engine, the valve 141 is closed, thereby preventing escape of fuel through the bleeder conduit 142. When the engine stops, however, the valve 141 opens, permitting the pressure to be dissipated after a predetermined time as determined by the setting of the valve 143. When the fuel pressure in chamber 133 has been dissipated, contacts 126, 127 are re-closed, and if the ignition switch 93 is still closed, the cranking operation will be repeated. It will 70 75

be understood that the pump 108 is amply capable of maintaining the fuel pressure at all times that the engine is rotating either forward or backward, irrespective of whether the bleeder passage is open or closed. The valve 141 is provided merely to prevent unnecessary operation of the pump while the engine is self-operative.

Although certain embodiments of the invention have been shown and described in detail, it will be understood that other embodiments are possible and that various changes may be made in the design and arrangements of the parts without departing from the spirit of the invention as defined in the claims appended hereto.

15 What is claimed is:

1. In combination with an internal combustion engine having a fuel system including an engine-driven fuel pump a starting system for the engine including a magnetic starting switch, a control circuit for said starting switch including a manual switch and a resistor having such a value as to limit the current in the control circuit to a holding value for the starting switch, a set of contacts normally bridging said resistance, means responsive to pressure generated by said fuel pump for opening said contacts, and means responsive to self-operation of the engine for deenergizing said control circuit.

2. In combination with an internal combustion engine, a starting system therefor including a magnetic starting switch, a control circuit for said switch including a resistor having such a value as to limit the current through the control circuit to a holding value for the starting switch, means for normally short-circuiting said resistor, means responsive to rotation of the engine in either direction for opening said short-circuiting means, and means responsive to self-operation of the engine for deenergizing said control circuit.

3. In combination with an internal combustion engine, a starting system therefor including a magnetic starting switch, a control circuit for said switch including a resistor having such a value as to limit the current through the control circuit to a holding value for the starting switch, means for normally short-circuiting said resistor, unitary means responsive to the rotation of the engine in either direction for opening said short-circuiting means, means responsive to the self-operation of the engine for deenergizing said control circuit, and means for preventing reclosure of the shorting means for a predetermined time after the engine stops.

4. In combination with an internal combustion engine having a fuel system including a pressure pump, a starting system, for said engine including a magnetic starting switch, a control circuit for said starting switch including a resistor having such a value as to limit the current through the control circuit to a holding value for the magnetic starting switch, means normally short-cir-

cuiting said resistor, and means responsive to pressure generated by said fuel pump for opening said short-circuiting means.

5. In combination with an internal combustion engine having a fuel system including a pressure pump, a starting system for said engine including a magnetic starting switch, a control circuit for said starting switch including a resistor having such a value as to limit the current through the control circuit to a holding value for the magnetic starting switch, means normally short-circuiting said resistor, means responsive to pressure generated by said fuel pump for opening said short-circuiting means, and means responsive to self-operation of the engine for breaking said control circuit.

6. In combination with an internal combustion engine having a fuel system including a pressure pump, a starting system for said engine including a magnetic starting switch, a control circuit for said starting switch including a resistor having such a value as to limit the current through the control circuit to a holding value for the magnetic starting switch, means normally short-circuiting said resistor, means responsive to pressure generated by said fuel pump for opening said short-circuiting means, means responsive to self-operation of the engine for breaking said control circuit, and means for dissipating said fuel pressure a predetermined time after the engine stops.

7. In combination with an internal combustion engine having a fuel system including an engine-driven fuel pump and an intake, starting mechanism for said engine including a starting switch, a control circuit for said switch including a resistor of a value to limit the current in the control circuit to a holding value for the starting switch, means normally short-circuiting said resistor, means for opening said short-circuiting means responsive to pressure generated by said fuel pump, and means for opening said control circuit responsive to vacuum in the fuel intake caused by self-operation of the engine.

8. In combination with an internal combustion engine having a fuel system including an engine-driven fuel pump and an intake, starting mechanism for said engine including a starting switch, a control circuit for said switch including a resistor of a value to limit the current in the control circuit to a holding value for the starting switch, means normally short-circuiting said resistor, means for opening said short-circuiting means responsive to pressure generated by said fuel pump, means for opening said control circuit responsive to vacuum in the fuel intake caused by self-operation of the engine, means for dissipating said fuel pressure a predetermined time after the engine stops, and means responsive to intake vacuum for rendering said pressure dissipating means inoperative.

PAUL H. MAURER. 60
